FLOOR GLIDE FOR A BED FRAME

Delmar C. Steinwedel, Seymour, Ind., and Stuart R. Paine,
Louisville, Ky., assignors to Seymour Industries, Inc.,
Seymour, Ind., a corporation of Indiana

Filed Jan. 10, 1966, Ser. No. 550

Term of patent 14 years

(Cl. D5—2)

FIG-2

FIG-1

FIG-4

FIG-3

FIG. 1 is a perspective view of a floor glide for a bed frame showing our new design;

FIG. 2 is a side elevational view thereof;

FIG. 3 is a bottom plan view thereof; and

FIG. 4 is a top plan view thereof.

We claim:

The device is characterized by a circular base having a bottom surface formed with a centrally positioned circular and generally flat portion and a gently upwardly sloping annular portion surrounding the flat portion and joining at the periphery of the base with a radially flat upper base surface, and an upstanding slidably tapered tubular support centrally formed on said base with its larger end smoothly flaring into the said upper surface of said base.

The ornamental design for a floor glide for a bed frame, substantially as shown and described.
